Primary Examiner — Doris Clark

(57) **CLAIM**

I claim the ornamental design for a resilient channel, as shown and described.

DESCRIPTION

FIG. 1 is a front perspective view of the resilient channel;
FIG. 2 is a front view of the resilient channel;
FIG. 3 is a left side view of the resilient channel;
FIG. 4 is a top view of the resilient channel;
FIG. 5 is a right side view of the resilient channel;
FIG. 6 is a right end view of the resilient channel; and,
FIG. 7 is a left end view of the resilient channel.
